CONDENSATION PREVENTING MEANS FOR
REFRIGERATORS

John K. Roth, San Francisco, Calif.

Application May 10, 1946, Serial No. 668,924

2 Claims. (Cl. 62—116)

1

The present invention relates to improvements in refrigerators, and has particular reference to refrigerating cabinets of the type generally known as frozen food cabinets, although the invention is not limited to this particular type and may be used wherever similar conditions prevail.

Cabinets of this character usually have door openings in the top thereof, with suitable doors for closing the openings and sealing means interposed between the doors and the door frames. A certain amount of cold air escapes through the door openings even when the doors are closed, and it is the principal object of the present invention to utilize this escaping air for producing a condenser effect in the refrigeration circuit, preferably of an auxiliary character, in order to relieve the conventional condenser of a portion of its load.

The top of a frozen food cabinet is usually made of insulating material covered by a sheet of stainless steel or similar metal, and the cold air escaping has a tendency to cool the stainless steel immediately surrounding the door opening to such an extent that moisture from the outside air settles and condenses on the steel resulting in drops of water collecting on the cabinet around the openings.

It is a further object of the invention to eliminate or reduce the condensation of water on the cabinet around the door openings by guiding the compressed and heated refrigerant from the compressor around the door openings, which thus serves the double purpose of heating the surrounding surface of the cabinet to prevent condensation of water on the latter and of condensing the refrigerant to relieve the conventional condenser.

Further objects and advantages of my invention will appear as the specification proceeds, and the new and useful features thereof will be fully defined in the claims attached hereto.

The preferred form of my invention is illustrated in the accompanying drawing, forming part of this application, in which:

Figure 1 shows a perspective view of a frozen food cabinet having my improvements embodied therein; and

Figure 2, a fragmentary vertical section through an edge portion thereof.

While I have shown only the preferred form of my invention, I wish to have it understood that various changes or modifications may be made within the scope of the claims hereto attached without departing from the spirit of the invention.

2

Referring to the drawing in detail, the cabinet 1 may be generally of conventional construction, having a bottom 2, side walls 3, end walls 4, and a top 5 having two door openings 6 and two doors 7 for closing the same.

The bottom, side walls and end walls are heavily insulated, as shown at 8, and the top is conventionally made of a layer of wood, or other material 9, the entire structure being covered by sheet metal 10, preferably stainless steel.

The doors 7 are made to project inside the door openings, as at 11, suitable gaskets 12 serving as sealing means, and the doors having flanges 13 overlying the edges of the door openings.

15 In spite of the sealing means, a certain amount of cold air escapes past the gasket and cools the stainless steel around the door opening to such an extent that moisture from the atmosphere condenses on the steel and leaves a film or drops of water on the cabinet, as may be readily seen by mere inspection of a conventional food cabinet in use.

The refrigerating apparatus is usually accommodated in the lower portion of the frozen food cabinet, and comprises in its principal features, a compressor 14 having a discharge conduit 15 leading to the condenser 16 which latter discharges into a receiving tank 17.

The refrigerant, which is now in liquid form, is then forced through the conduit 18 and an expansion valve (not shown) into the evaporator (not shown), which consists of a coil mounted in the walls of the cabinet, and finally returns to the intake side of the compressor in vaporized form 35 through the conduit 19.

While the temperatures may vary with different installations, in a typical example, the temperature of the gas leaving the compressor may be approximately 120° F., that of the liquid in the receiver about 65°, and that prevailing in the evaporator 0°, while the gas returns to the compressor at about 20°.

The circuit thus far described is conventional. The principal features of the present invention 45 is a by-pass conduit 20 which connects to the discharge side of the compressor, as at 21, passes through the wall of the cabinet and around the door openings, and then returns to the receiver, as at 22, thus by-passing the condenser.

50 While the structural arrangement may be made in any suitable manner to accomplish the object of the invention, I provide, adjacent the door opening, a groove 23, in which the by-pass conduit is accommodated, immediately underneath the sheet metal covering.

Where two door openings are employed, as in

the drawing, I guide the conduit around the two openings and double the conduit upon itself between the openings, as at 28', so as to cover all edges of the openings as completely as possible.

In operation, part of the refrigerant will pass through the conventional condenser 16 in the usual manner. But, another part of the refrigerant will pass through the by-pass 20 in heat-exchange relation with the cold air escaping around the rim of each door, which absorbs heat 10 units from the by-pass.

Thus my by-pass takes the place of an auxiliary condenser which delivers the refrigerant back to the receiver at substantially the same temperature as does the main condenser. The same 15 condenser effect takes place when the doors are moved for gaining access to the interior of the cabinet, while removing frozen foods therefrom.

The by-pass conduit, at the same time increases the temperature of the steel top of the cabinet to approximately room temperature and thereby substantially prevents condensation of room moisture on the cabinet so as to keep the latter 20 perfectly dry.

I claim:

1. A refrigerator comprising a cabinet made of insulating material and having sheet metal covering the said material, the cabinet having a door opening in the top thereof and a door for closing the same, with a rim of the door projecting over the rim of the door opening, a refrigerating circuit including a compressor, a condenser connected thereto and a receiver connected to the condenser, and a by-pass for the condenser

leading around the door opening outside the door rim and in direct heat-exchange relation with the sheet metal covering whereby a portion of the compressed refrigerant is guided around the door opening to reduce the settling of moisture from outside air upon the metal covering.

2. A refrigerator comprising a cabinet made of insulating material and having sheet metal covering the said material, the cabinet having a door opening and a door for closing the same, with a rim of the door projecting over the rim of the door opening, a refrigerating circuit including a compressor, a condenser connected thereto and a receiver connected to the condenser, and a by-pass for the condenser leading around the door opening outside the door rim and in direct heat-exchange relation with the sheet metal covering whereby a portion of the compressed refrigerant is guided around the door opening to reduce the settling of moisture from outside air upon the metal covering.

JOHN K. ROTH.
